UNITED STATES PATENT OFFICE.

GUSTAV B. PETSCHÉ, OF YONKERS, NEW YORK.

ROTARY COMPRESSOR.

1,380,016.

Specification of Letters Patent. Patented May 31, 1921.

Application filed October 6, 1920. Serial No. 415,144.

To all whom it may concern:

Be it known that I, GUSTAV B. PETSCHÉ, a citizen of the United States of America, and resident of Yonkers, county of Westchester, 5 State of New York, have invented a certain new and useful Improvement in Rotary Compressors, of which the following is a true and exact description, reference being had to the accompanying drawings, which 10 form a part thereof.

My invention relates to rotary compressors of the kind in which the piston is made up of a rotating eccentric ring provided with an extension which forms a partition 15 between the admission and delivery side of the pump. The object of my invention is to provide such a pump with a valve working in connection with its delivery port to lift automatically as is the case with ordinary pump valves and a valve actuating cylinder and piston so connected with the compression side of the pump that the valve will be closed rapidly at the end of the delivery cycle of the piston. This and other 20 features of my invention will be best understood as described in connection with the drawings in which they are illustrated and in which—

Figure 1 is a side elevation of the pump 30 taken on the section line 1—1 of Fig. 2.

Fig. 2 is a front elevation partly shown in section on the line 2—2 of Fig. 1, and

Fig. 3 is a view similar to Fig. 1 showing a modified form of my invention.

35 A, A, indicate twin compressor cylinders formed in the same casting and having face plates A² and A³. B indicates the cylindrical periphery of the compressor cylinder A. C is a bearing surface in the form of the 40 segment of a cylinder formed in the casing. D is the admission port formed, as shown, through the bearing surface C and leading into an admission passage D'. E is a delivery port having formed in it a valve seat E'. E² is the receiving chamber of the pump. F is the driving shaft on which is secured eccentrics indicated at F' on which are supported the eccentric rings G forming the pistons of the compressor. H is an 45 extension of the piston ring G forming a partition between the admission and delivery sides of the compression cylinder and forming at its end a tight joint indicated at I with a valve fulcrum at I², the lower 50 face of which forms a solid partition, free from openings. The circumferential sur-

face is provided with bearing faces J and M. Between J and M there are recesses K and C' which communicate with D', the admission chamber, through ports K'. K² 60 and K³ are ports opening on the face of the bearing C as indicated and communicating with a passage K⁴ which leads into the top of a cylinder L. K⁵ is a passage leading from the bottom of a cylinder L to 65 the atmosphere or into the admission chamber D' as shown in dotted lines through a regulating cock indicated at K⁷. K⁶ is a regulating screw by which the passage K² can be regulated. O is a piston secured to 70 the delivery valve stem M' and working in the cylinder L and N is the delivery valve working in connection with the valve seat E'.

In the modification shown in Fig. 3 C' 75 is the delivery valve seat in the form of a grid and n is a grid slide valve moving on it in the delivery chamber c. n' is the valve stem having secured to it a plunger l' moving in a dash pot cylinder o' and in cylinder 80 o and a piston l also moving in cylinder o. The ports K², K³ and K⁴ communicate with cylinder o' as they do with cylinder O in Fig. 1. K⁵ is a port connecting with the bottom of cylinder o' and having a regulator K⁷. p is a port leading from the delivery side of the compressor to the bottom of cylinder o.

In operation the piston rotates in a clockwise direction and at the beginning of a 90 compression cycle the slide J M is in a position in which its valve portion M opens the admission port D while its portion J closes the port K³ and opens the port K² through the passages K and C' and the port 95 K' to the admission chamber of the compressor. The valve N is, of course, seated and held to its seat by the receiver pressure. At the close of the compression cycle of the piston the slide is shifted to the position shown in Fig. 1, the admission port D being closed by the portion M while the portion J opens the port K³ and closes the port K². The compressed fluid on the delivery side of the pump can then pass through the 100 passage K⁴ into the top of the cylinder L where, acting against the piston O, it acts to promptly and firmly seat the valve N so that there can be no back flow into the cylinder at the time when the piston is 110 passing from contact with the point B' to the point B². During the succeeding com-

pression cycle of the piston the slide shifts its position so as to close the port K^3 and open the port K^2 permitting any compressed fluid in the top of the piston L to escape freely into the admission chamber and leaving the valve M in position to open freely for the outflow of compressed fluid. The port K^5 serves simply to permit the escape of fluid from the bottom of the cylinder O and the adjusting cock K^7 permits such resistance to this outflow as will prevent the valve M from striking its seat too rapidly.

In the construction shown in Fig. 3 I employ a slide valve instead of a puppet valve and necessarily employ in connection with it means for opening it at the proper time as well as closing it. The plunger l' and piston l constitute a differential piston. Gas from the delivery side of the compressor passes to cylinder o through port p and, when the pressures on both sides of valve n are equal the pistons move up opening the valve. At the end of the compression stroke the gas is admitted to the top of cylinder o through ports K^3 , K^4 , and acting on the larger diameter of piston l depresses it and closes valve n . In other respects this construction operates like that of Fig. 1.

Having now described my invention, what I claim as new and desire to secure by Letters Patent, is:

1. In a rotary compressor having a rotary eccentric ring piston provided with an extension forming a division between the admission and discharge sides of the cylinder, admission and discharge ports in communication with the pump cylinder, a valve for closing the discharge port, a cylinder and piston for actuating said valve to close it, a port leading from the discharge side of the compressor to said cylinder and a valve actuated by the moving parts of the compressor normally closing said port but opening it near the end of the compression cycle of the piston.

2. In a rotary compressor having a rotary eccentric ring piston provided with an extension forming a division between the admission and discharge sides of the cylinder, a slide bearing and a slide connected to the piston extension, the combination with a delivery port on one side of the compressor, of a valve for closing said port, a cylinder and piston for actuating said valve to close the port, a passage leading from the cylinder to two ports in the slide bearing one of said ports located to connect with the delivery side of the compressor and the other to exhaust and a valve moving with the piston

extension formed to open and close said ports as described.

3. In a rotary compressor having a rotary eccentric ring piston provided with an extension forming a division between the admission and discharge sides of the cylinder, admission and discharge ports to the pump cylinder, a valve for closing the discharge port, a cylinder and piston for actuating said valve to close it, a port leading from the discharge side of the compressor to said cylinder, a valve actuated by the moving parts of the compressor normally closing said port but opening it at the end of the compression cycle of the piston and a valve also actuated by the moving parts of the compressor and operating to close the admission port of the compressor during the period when the piston is out of contact with the compressor cylinder.

4. In a rotary compressor having a rotary eccentric ring piston provided with an extension forming a division between the admission and discharge sides of the cylinder, a slide bearing and a slide connected to the piston extension, the combination with a delivery port on one side of the compressor, of a valve for closing said port, a cylinder and piston for actuating said valve to close the port, a passage leading from the cylinder to two ports in the slide bearing, one of said ports located to connect with the delivery side of the compressor and the other to exhaust, a valve moving with the slide connected with the piston extension and formed to open and close said ports as described and a second valve moving with the slide aforesaid and acting to close the admission port of the compressor during the period when the piston is out of contact with the compression cylinder.

5. In a rotary compressor having a rotary eccentric ring piston provided with an extension forming a division between the admission and discharge sides of the cylinder, admission and discharge ports in communication with the pump cylinder, a valve for closing the discharge port, means actuated by the pressure on the discharge side of the compressor for opening said valve, means consisting of a cylinder and piston also actuated by the pressure on the discharge side of the compressor for closing the valve and a valve actuated by the moving parts of the compressor for controlling the admission of compressed gas to the valve closing cylinder.

GUSTAV B. PETSCHE,
